UNITED STATES PATENT OFFICE.

WILLIAM HALKYARD, OF PROVIDENCE, RHODE ISLAND.

METHOD OF ATTACHING BUTTONS TO SHOES, &c.

SPECIFICATION forming part of Letters Patent No. 299,133, dated May 27, 1884.

Application filed January 2, 1884. (No model.)

To all whom it may concern:

Be it known that I, WILLIAM HALKYARD, a citizen of the United States, residing at Providence, in the county of Providence and State 5 of Rhode Island, have invented certain new and useful Improvements in Methods of Attaching Buttons to Shoes, &c.; and I do hereby declare the following to be a full, clear, and exact description of the invention, such as will 10 enable others skilled in the art to which it app pertains to make and use the same, reference being had to the accompanying drawings, and to letters or figures of reference marked there on, which form a part of this specification.

15 My invention relates to an improved method of attaching buttons to shoes, &c.; and it consists, first, in passing a staple through the button-eye, then inserting the staple through a flanged eyelet, after which both the eyelet and 20 staple are inserted through the leather or fabric, and clinched thereunder at one operation by suitable means, thereby forming a very strong, efficient, and comparatively inexpensive button-fastener, as will be more fully hereinafter set forth.

25 In the annexed sheet of drawings, Figure 1 represents in vertical central section my improved fastener applied to the fabric or material with button, &c., complete and ready for 30 clinching or setting. Fig. 2 represents the same clinched. Fig. 3 represents a top view of the same with button removed. Fig. 4 represents an inverted or under view of the same when clinched.

35 Referring now to the drawings, I make use of an eyelet, A, having a flange, a, said eyelet adapted to be inserted through the fabric E and project beyond the same at a', the flange a thereof resting upon the surface of the fabric, as shown.

40 B represents a staple provided with the center loop or eye, b², adapted to receive the shank of a button, D, the prongs of the staple terminating in the oppositely-beveled, and sharp- 45 ened points b', all as fully shown in Fig. 1.

The manner of fastening buttons to fabrics according to my present invention is as follows: I first pass the staple B through the shank of the button D and into the eye b², then 50 I insert the prongs of said staple into the neck of the eyelet A, the eye b² of said staple resting upon the flange a, thereby extending the

prongs of the staple beyond the eyelet, as shown, Fig. 1. I now next place the whole within the jaw or member of a suitable setting-instrument adapted to receive the same. The fabric now being placed in position, the manipulation of the setting-instrument forces at once both the staple and eyelet (unless previously perforated) through the fabric, Fig. 60 1, when, finally, the die of the other jaw of the instrument is forcibly brought into contact with the projecting portions of the staple and eyelet, thus completing the attachment, as shown in Fig. 2, which results in the ends of 65 the eyelet being bent and clinched into the fabric, and the prongs of the staple being also bent and clinched exterior to the eyelet, thereby producing a fastening much stronger than when attaching-prongs simply are used, as in 70 the latter case the clinched prongs are frequently torn from the fabric or leather when in use, especially so when applied to thin stock. With my invention this defect is wholly overcome.

75 I prefer in practice to have the prongs of the staple B to just fill the interior of the eyelet laterally, as shown in Fig. 1.

I do not claim herewith means for attaching my improved button-fastener, as the same has 80 been made the subject of a separate application for United States Letters Patent, filed upon even date herewith. Neither do I claim, broadly, means for re-enforcing or protecting the fabric.

85 Having thus described my invention, what I claim as new, and desire to secure by Letters Patent, is—

The method of attaching buttons to fabrics, &c., herein described, which consists, first, in 90 passing a staple through the eye or shank of the button, then inserting said staple through the neck of a flanged eyelet, after which the eyelet and staple are inserted through the fabric and clinched thereunder by suitable means 95 at one operation, substantially as shown and set forth.

In testimony whereof I have affixed my signature in presence of two witnesses.

WILLIAM HALKYARD.
